UNITED STATES PATENT OFFICE.

SAMUEL PETERS, OF SYDNEY, NOVA SCOTIA, CANADA.

HORSE-COLLAR FASTENING.

SPECIFICATION forming part of Letters Patent No. 244,657, dated July 19, 1881.

Application filed December 6, 1880. (No model.)

To all whom it may concern:

Be it known that I, SAMUEL PETERS, of Sydney, Cape Breton county, Province of Nova Scotia, Dominion of Canada, have invented a new and useful Improvement in Horse-Collar Fastenings, of which the following is a specification.

Figure 1 is a perspective view of the improvement shown open and applied to a horse-collar; and Fig. 2 is a front elevation of the improvement closed.

Similar letters of reference indicate corresponding parts.

The object of this invention is to provide the extremities of the horse-collar with a fastening whereby the collar can be conveniently opened and closed, and thereby readily adjusted to or removed from the neck of the animal.

The invention consists in constructing a horse-collar fastening of two plates or links hinged to each other at one end, curved in reverse directions, and connected with the end parts of the collar by loops, one of which is flexible and made longer than the other, so that the two plates or links can be shut together and closed down upon the top of the collar, as will be hereinafter fully described.

A represents a horse-collar which is made open at the top.

B is a plate, of metal or other suitable material, which is curved to fit upon the top of the collar A when the ends of the collar are brought together, and which is made of such a length as to overlap the outer sides of the ends of the collar, as shown in Fig. 2.

To one end of the plate B is hinged a second plate, C, which is made a little shorter than the plate B, and is curved correspondingly; but in the reverse direction, as shown in Fig. 1, so that when the two plates are swung together or closed the plate C will fit against the plate B, as shown in Fig. 2. One or both the plates B C may be made in skeleton or link form. The free end of the plate B is attached to a loop, D, of leather or other suitable material, which is attached, by sewing or other suitable means, to the outer side of one part of the collar A, at a little distance from the end of the said part. The free end of the plate or link C is attached to a loop, E, of leather or other suitable flexible material,

which is attached, by sewing or other suitable means, to the outer side of the other part of the collar A, at a little below its upper end. 55 The flexible loop or strap E is made of such a length as to pass over the top of the collar A and allow the two plates B C to close upon each other and upon the top of the collar A.

The fastening is opened by raising the hinged 60 ends of the plates B C, which causes the said plates to open, as shown in Fig. 1, and allows the collar A to be put on and taken off the horse without any danger of injuring his eyes. The fastening is closed by pressing the plate 65 C in beneath the plate B and drawing the hinged ends of the two plates downward. When the fastening is closed the strain upon the loop or strap E draws the plates B C downward snugly upon the top of the collar A, so 70 that the collar will be securely fastened, and cannot be unfastened without raising the hinged ends of the plates B C. With this construction the fastening can easily be fastened and unfastened in the dark, as the various 75 parts of the fastening are permanently connected.

I am aware that a shoe-fastening has been used with a bifurcated piece secured to one flap of the shoe and pivoted to a curved link 80 attached to the other flap, the link being prolonged to form a handle; but this device could not be used on a horse-collar, because the link or plate C must not extend beyond the plate B when folded, as the fastening could not be 85 opened if attached to a plate or rigid substance, while the whole object of my invention is to make a fastening that is easily opened and closed.

The device may be advantageously employed as a fastening or buckle for shoes. 90

What I claim as new and of my invention is—

The two reversely-curved and end-hinged plates B C, combined with loops D E, arranged on opposite ends of collar, the one, D, being set back from the end and the other, E, folding across the ends of the collar and under the plates B C, as shown and described. 95

SAMUEL PETERS.
